APRON FOR SCRAPERS

Benjamin E. Lindquist, Turlock, Calif.

Application November 30, 1946, Serial No. 713,300

3 Claims. (Cl. 37—118)

1

This invention relates in general to improvements in an earth working implement, namely, a carrying scraper of the type which includes a front end loading bowl, and a front apron mounted for cooperation with the open front end of said bowl.

One object of the present invention is to provide a carrying scraper wherein the apron is power-actuated for arcuate swinging movement from a position in advance of the bowl, through the forward portion of the bowl in sweeping relation over the cutting blade, to a position in the bowl rearwardly of said blade, whereby an accumulation of earth at the blade may be swept into the bowl independent of forward motion of the implement. In this manner capacity loading of the bowl is facilitated.

Another object of the invention is to articulate the apron, intermediate its upper and lower edges, on a transverse, horizontal axis whereby the lower section of said apron may hinge or swing relatively rearwardly and upwardly as the apron moves forward on the return stroke of its cycle of movement; this action of the lower section permitting the apron to clear or ride over loose and heaped earth accumulated at the blade after the apron has passed on each rearward or loading stroke.

A further object of the invention is to provide a novel power actuated mount for the apron.

A further object of the invention is to provide a practical apron for scrapers, and one which will be exceedingly effective for the purpose for which it is designed.

These objects are accomplished by means of such structure and relative arrangement of parts as will fully appear by a perusal of the following specification and claims.

In the drawings:

Fig. 1 is a side elevation, mainly in section, of a carrying scraper embodying the present invention; the earth loading apron being shown in its starting position in broken lines; in its position sweeping across the blade in full lines; and at the end of its rearward or loading stroke in dotted lines.

Fig. 2 is a similar view, but shows the manner in which the lower section of the apron hinges rearwardly and upwardly on the forward or return stroke of said apron, whereby to clear accumulated earth heaped at said blade.

Referring now more particularly to the characters of reference on the drawings, the invention is here shown as embodied in a carrying scraper which includes generally a main frame 1, vertically adjustably supported at its forward end by structure indicated in part at 2, and wheel-supported at its rear end, as at 3.

An earth receiving and carrying bowl 4 is mounted in the frame 1, and said bowl, which is open at its forward end, is provided at the front edge of the bottom 5 with a transverse cutting

2

and digging blade 6. The bowl 4 is adapted to be unloaded by means such as a vertically movable, rear end gate, indicated diagrammatically at 7.

The present invention resides in the form, mounting, and operation of the front apron of the scraper; such apron being indicated generally at 8. The apron 8 extends transversely of the implement and is substantially the same height as the bowl, and of a length so that it may move lengthwise of the implement between the side plates of said bowl.

The apron 8, which will hereinafter be described in detail, is suspended by a pair of transversely spaced arms 9 which extend upwardly to rigid connection with a horizontal cross shaft 10, such arms being forwardly curved, as shown. The horizontal cross shaft 10 is journaled, adjacent its ends, in connection with rigid posts 11 which upstand from opposite sides of the main frame 1 adjacent the front end of the bowl; such cross shaft being disposed generally in vertical alignment with the cutting and digging blade 6. The apron 8 is thus mounted for arcuate swinging motion from a starting position ahead of the open front end of the bowl, into said bowl over the blade 6 and to a position at the end of its stroke in the bowl some distance to the rear of said blade, but relatively elevated. As shown in Fig. 1, these three positions are shown in broken lines, full lines, and dotted lines, respectively.

The horizontal cross shaft 10 is rocked to swing the apron 8 through its cycle of arcuate movement; i. e. through a rearward loading stroke, followed by a forward return stroke, by means of the following power unit:

A radial lever 12 is fixed on and projects downwardly from the shaft 10, and is pivotally connected at its lower end with a clevis 13 on the forward end of a piston rod 14 which extends outwardly from a fluid-pressure actuated power cylinder 15 of double-acting type. This power cylinder 15 extends lengthwise of the implement, and is pivoted at its rear end, as at 16, in connection with a bracket 17 on the main frame 1. The double-acting power cylinder 15 is controlled by a fluid pressure system, here shown only in part at 18, but which system extends forwardly to the tractor to which the scraper is connected and is there valve-controlled by the tractor operator.

The apron 8 is sectional, comprising an upper transverse section 19 and a lower transverse section 20, said sections being hinged or articulated at adjacent edges on a transverse horizontal axis, as at 21, for relative rearward and upward swinging motion of the lower section 20. The lower section 20 is fitted, on the front side, with a pair of transversely spaced ribs 22, which ribs correspond to the mounting arms 9, which are rigidly affixed to the front side of the upper section 19. At adjacent ends the arms 9 and ribs

22 project in overlapping relation, as at 23, whereby to form stops limiting forward hinging or articulating motion of the lower section 20 to the position shown in Fig. 1.

At their ends the upper and lower apron sections 19 and 20 are provided with rearwardly projecting side wings, the upper side wings being shown at 24, and the lower side wings being shown at 25. Adjacent upper and lower side wings 24 and 25 lap each other, in cooperative relationship at all times, and serve to prevent lateral spillage of loose earth from the apron when the same is working.

When the scraper is in operation and loading, the bowl 4 is lowered so that the blade 6 engages the earth in a cutting and digging position. At intervals the operator causes the power cylinder 15 to actuate so as to swing the apron 8 through its previously described rearward, loading stroke. Upon such stroke the apron 8 engages the accumulation of earth adjacent and above the cutting blade, sweeping such earth rearwardly into the bowl 4. In this manner loading of the scraper is materially facilitated, and maximum loads can be obtained. Additionally, the dirt friction at the blade 6 is relieved, permitting of more effective action of said blade.

When the apron 8 reaches the rear end of its loading stroke, the double-acting power cylinder 15 is reversed, whereupon said apron traverses its forward or return stroke. To avoid retardation of such stroke by the heap of loose earth which has accumulated at the blade 6, after passage of the apron on its loading stroke, which heap is indicated generally at 26, said apron is articulated in the manner described. Thus, upon its forward, return stroke the lower section 20 of the apron hinges rearwardly and upwardly and rides over the heap 26 without drag being imposed upon the power unit. Once the apron has cleared the heap 26 the lower section 20 is of course free to return to its starting position, as shown in broken lines in Fig. 1.

The described apron arrangement is simple, yet rugged, in its construction and will serve the intended purpose with a minimum of maintenance or repair; the direct connected power cylinder 15 affording a powerful but smooth operating means for swinging the apron through its cycle of movement.

From the foregoing description it will be readily seen that there has been produced such a device as substantially fulfills the objects of the invention as set forth herein.

While this specification sets forth in detail the present and preferred construction of the device, still in practice such deviations from such detail may be resorted to that do not form a departure from the spirit of the invention as defined by the appended claims.

Having thus described the invention, the following is claimed as new and useful and upon which Letters Patent are desired:

1. An apron unit for a carrying scraper which includes a bowl open at its front end and having a digging blade at the bottom of said end, the unit comprising posts upstanding from the bowl on opposite sides adjacent its open end, a cross shaft journaled in connection with the posts, power means operative to reversibly rotate said shaft, arms fixed on and depending from the shaft, and an apron mounted on said arms for swinging motion in a cycle lengthwise of the scraper upon reverse rotation of the shaft, said

cycle including a rearward loading stroke and a forward return stroke, the apron traversing a path, on its loading stroke, extending from a starting position ahead of the blade, into the bowl over the blade, to a position in the bowl rearwardly of the blade; the apron being articulated for relative rearward hinging motion of the lower portion thereof from a normally dependent position.

2. An apron unit for a carrying scraper which includes a bowl open at its front end and having a digging blade at the bottom of said end, the unit comprising an apron disposed adjacent and in cooperative relation to the open front end of the bowl, means mounting the apron for motion in a cycle lengthwise of the scraper, said cycle including a rearward loading stroke and a forward return stroke, the apron traversing a path, on its loading stroke, extending from a starting position ahead of the blade, into the bowl over the blade, to a position in the bowl rearwardly of the blade, the apron including an upper section and a lower section, means hinging said sections together at adjacent edges on a transverse horizontal axis for relative rearward hinging motion of the lower section from a normally dependent position, stop means to prevent relative forward hinging motion of the lower section from said normally dependent position, and power means operative to effect such cycle of motion of the apron; said apron mounting means being arranged so that on each stroke the apron traverses an arcuate path whose intermediate portion is lower than its end portions.

3. An apron unit for a carrying scraper which includes a bowl open at its front end and having a digging blade along the front edge of the bottom of the bowl, such unit comprising supports on the sides of the bowl projecting vertically in substantially the same vertical plane as that in which lies the front edge of the bottom of the bowl, a shaft journaled in the upper ends of the supports, means to oscillate the shaft, downwardly projecting arms fixed to the shaft, an apron fixed to said arms, the overall length of the arms and apron being substantially the same as the distance between the axis of the shaft and the front edge of the bottom of the bowl whereby when the shaft is oscillated the apron may be moved through an arc lengthwise of the bowl and from a position forwardly of the front edge of the bottom of the bowl to a position rearwardly thereof and within the bowl with the front edge of the bottom of the bowl lying tangent to said arc, the apron being in part collapsible in a rearwardly direction whereby to allow it to swing out of the way of and ride over accumulated dirt in the bowl as the apron is swung from within the bowl to a position forwardly of the bowl.
